CLAIM

We claim the ornamental design for a light fixture, as shown and described.

DESCRIPTION

FIG. 1 is a perspective view of a light fixture showing our new design.

FIG. 2 is a front view of the light fixture shown in FIG. 1. FIG. 3 is a rear view of the light fixture shown in FIG. 1. FIG. 4 is a first side view of the light fixture shown in FIG. 1.

FIG. 5 is a second side view of the light fixture shown in FIG. 1.

FIG. 6 is a plan view of the light fixture shown in FIG. 1. FIG. 7 is a bottom view of the light fixture shown in FIG. 1. FIG. 8 is a perspective view of a light fixture showing another embodiment of our new design.

FIG. 9 is a front view of the light fixture shown in FIG. 8. FIG. 10 is a rear view of the light fixture shown in FIG. 8. FIG. 11 is a first side view of the light fixture shown in FIG. 8.

FIG. 12 is a second side view of the light fixture shown in FIG. 8.

FIG. 13 is a plan view of the light fixture shown in FIG. 8; and,

FIG. 14 is a bottom view of the light fixture shown in FIG. 8.

The bottom views are not part of the claimed design. The elements of the light fixture shown in broken lines form no part of the claimed design.
